to the rear side of the envelope body and the other is being centrally attached to the flap of the envelope. The button and string fastening means permits the envelope to be easily opened and resealed a plurality of times. This is a great convenience in any application where the envelope is reused, as for transporting interoffice and interplane communications, where the envelopes are used for storage purposes, or for cities, nations, and the like. For such purposes, the button and string fasteners are vastly superior to metal fasteners used for the same purpose, which have a relatively short life.

The provision of button and string fasteners adds to the cost of an envelope set, so that it is not economically feasible for the manufacturer to stock common and graded envelopes fastened in this manner, unless he has frequent need for such envelopes. It is, of course, unnecessary for one to use an envelope provided with a temporary fastening device by sealing the adhesive coated flap in the conventional manner. Most small office have come to require a fastened envelope having temporary fastening means, although this demand is not sufficiently warrant regular stocking of such envelopes. It is for this large group of consumers that the present invention is particularly addressed.

It is the principal object of this invention to provide a fastening means consisting of a pair of fasteners attached to one side of a flexible base sheet, the opposite side of the base sheet being provided with an adhesive layer and the base sheet being adapted to be easily torn from the base of the fastening buttons to the flap of an envelope and adherence of the other fastening button to the rear body of an envelope, so as to close a conventional envelope to one having a temporary closure.

It is another object of this invention to provide temporary fastening means for securing small packages, rolls of sheet material, and the like.

Other objects of the invention will become apparent as the same numerals refer to corresponding parts and in which:

FIGURE 1 is a plan view of the fastening means according to this invention;

two approximately equal sized segments 13 and 14. FIGURE 2 is a plan view of a flexible base sheet provided with a button fastening element 16 secured to the base sheet by means of an adhesive or pressure sensitive element 17. The button element is preferably reinforced on the reverse side of the base sheet by means of a flat reinforcing element 18, as shown for example in FIGURE 3. FIGURE 4 shows that segment 14 of the flexible base sheet is provided with an identical button fastening element with the exception that a length of a stripable film material 21 is secured to the backing sheet on the same side as the buttons along with the disc 16 by means of the cyclets 17. The strip 19 is bent at each end to pass it to extend to the other button and be wrapped several times around the shank of that button. Preferably it is several times the maximum length and is from about 4 inches to one foot long.

Although shown to be circular in shape, the disc or washer element 16 may be in the shape of triangles, squares, hexagons, or other polygonal shapes as desired. Likewise, the shape of the reinforcing element 18 is immaterial, provided it is relatively formed from relatively thin, but stiff, fiber board, card board, or heavy kraft paper, or the like, although they may, if desired, be relatively thick, thin synthetic resinous plastic material or metal is desired. The cyclets 17 are preferably formed of metal such as brass or aluminum, or, depending in some instances, synthetic resinous plastic cyclets such as acetal, polycarbonate, polycid, and butyrate may be used.

The side of the flexible base sheet opposite to the button fastening elements is provided with a thin layer of adhesive material 20 as shown in FIGURE 2. The adhesive material 20 is preferably a moisture sensitive substance such as animal glue, or for some purposes, however, it is desirable to employ a pressure sensitive adhesive material. This is illustrated in the modified form of the invention shown in FIGURE 4, where the fastening means 16A is provided on its rear surface with a layer of pressure sensitive adhesive material 20A. A layer of thin stripable film material 21 is applied over the layer of pressure sensitive adhesive.

When the stripable film 21 is easily torn from around the shank of the cyclet 17 and the reinforcing element 18 when the adhesive layer and the stripable film are applied to the base sheet before the button fastening element 16 is applied, the stripable film material 21 may be applied to the backing sheet as the first step in the production of the closure means, although the adhesive may, if desired, be applied at any stage in the manufac-

The other segment 14 of the fastening means bearing the button fastening elements 16 and 18 is adapted to be adhesively secured to the center of the flap 23. As shown, the string 19 may be criss-crossed several times from one button to the other and then wound around the shanks. The string is wound once or more times around one of the button shanks. The broadened bases of the fastener base segments, which are adapted to be passed around the elements of the invention, distribute the stresses upon the fastener over a wide area to provide a strong closure. By this means the envelope 22 may be provided with a temporary closure enabling it to qualify for third class mailing or to be opened and closed repeatedly without wearing out the closure means. It is believed, however, that the fastening means of this invention may be used to convert envelopes of all sizes, shapes, materials, and the like.

Referring to FIGURE 5, there is here shown a further use for the closure means of this invention. The fastener 16 is used to secure a roll of sheet material 24 against unbinding much in the manner of a rubber band. The back surface of the flexible base sheet may be adhesively secured to one outside edge of the roll of sheet material. If desired, the fastening means may simply be temporarily held by the finger or thumb until the string 19 has been passed around the roll of sheet material 24 and 45 wrapped several times around the opposite button.

On the other hand, if the roll of sheet material is of such large diameter that the string 19 does not pass around it and leave sufficient length of string to be wrapped around the opposite button, then the fastening means 16

20 a layer of adhesive material on the side of the base sheet 21 opposite the button 16, a line of perforations being substantially across the base sheet along the line of abutment of said equilateral triangles between the button fastener elements 16 and 18. The base sheet may be cut 25 into two segments, each bearing a button fastening element, one only of said button fastening elements bearing a portion of the string from the first element and the other of said button fastening elements being adapted to receive a portion of the string from the first element. Said button fastening elements are spaced so that the base sheet generally spaced inwardly from the apices of said equilateral triangles and said line of perforations being generally spaced inwardly from the base sheet.

2. A closure means according to claim 1, further characterized in that said adhesive material is a moisture sensitive glue.
